ARTICLE

George Gault, New York, N. Y.

Application October 25, 1951, Serial No. 17,117

Term of patent 14 years

(Cl. D42—10)

To all whom it may concern:

Be it known that I, George Gault, a citizen of the United States, residing at New York city, in the county of New York and State of New York, have invented a new, original, and ornamental Design for a Watch and Clock Dial or Similar Article, of which the following is a specification, reference being had to the accompanying drawing, forming part thereof.

The figure is a face view of a watch and clock dial or similar article, showing my new design, which is of no appreciable thickness.

I claim:

The ornamental design for a watch and clock dial or similar article, as shown and described.

GEORGE GAULT.
